TRUCK

Fred E. Bachman, Chicago, Ill., assignor to
American Steel Foundries, Chicago, Ill., a cor-
poration of New Jersey

Application August 6, 1934, Serial No. 738,674

26 Claims. (Cl. 105—197.1)

This invention pertains to car trucks.

It is an object of this invention to provide improved and economical trucks wherein loads are supported by springs of different character.

Another object is to provide a truck construction wherein coil and elliptic springs are used to simultaneously support loads and wherein spring capacity is greatly increased over similar types of trucks.

A further object is to provide a truck construction wherein a movable bolster is used supported by coil and elliptic springs on adjacent frame structure.

With these and various other objects in view, the invention may consist of certain novel features of construction and operation, as will be more fully described and particularly pointed out in the specification, drawings and claims appended hereto.

In the drawings, which illustrate an embodiment of the device and wherein like reference characters are used to designate like parts—

Figure 1 is a side elevation of one form of truck construction embodying the invention;

Figure 2 is an end elevation, partly in section, of the truck construction illustrated in Figure 1, the section being taken substantially in the plane of the transverse center line of the truck;

Figure 3 is a side elevation of another modified form of truck construction embodying the invention;

Figure 4 is an end elevation, partly in section, of the truck construction illustrated in Figure 3, the section thereof being taken substantially in the plane of the transverse center line of the truck and having certain parts omitted; and

Figure 5 is a transverse fragmentary sectional elevation of a slightly modified form of truck embodying the invention, the same being taken substantially in the plane of the transverse center line of the truck.

The subject matter of Figures 1 to 4 inclusive, of this application have been divided out of application Serial No. 543,763, filed June 12, 1931, where they appeared as Figures 7 to 10 inclusive, this application now having matured into United States Patent No. 2,051,630, granted August 18, 1936.

Referring first of all more particularly to the truck construction illustrated in Figures 1 and 2, the side frame 120 is provided with the tension and compression members 122 and 124 merging adjacent their ends, being provided with the journal boxes 126. The journal boxes accommodate the ends of the axle 128 of the wheel and axle

assembly 130 which may be of any desired type, such as the friction or Simplex. The tension and compression members of the side frame are integrally connected by the spaced column guides 132 forming a window in the side frames. The side frames are connected by means of the transversely extending spring plank 134 extending within said window, the spring plank being preferably upwardly flanged as at 136.

The bolster 138 extends within the windows 10 and is provided with guide portions 140 cooperating with the column guides 132, the bolster being provided with the center bearing 141 and side bearings 143. The tension member 122 is provided with raised coil spring seats 142 and the bolster is provided with coil spring seats 144 between which the coil springs 146 are disposed. The bolster is provided with a leaf spring seat 148 disposed inwardly of the side frames and accommodating the leaf or semi-elliptic springs 150, said spring seat 148 being substantially in vertical alignment with the side bearings 143. The semi-elliptic springs are spaced between the coil springs 146 and the outer ends thereof are provided with suitable shoes 152 supported on the spring plank 136 directly within the window of the side frame. The opposite end of the leaf springs is provided with a suitable shoe 154 pivoted as at 156 to the link 158, the opposite end of the link being pivoted as at 160 to the bolster. 30

In the construction shown in Figures 3, 4 and 5, the side frame 160 is provided with the tension and compression members 162 and 164 merging adjacent their ends and provided with the journal boxes 166. The tension and compression members are connected by means of the column guides 168 forming a window, the bottom chord thereof being substantially on one level. The journal boxes accommodate the ends of the axle 170 of the wheel and axle assembly 172, and the side frames are connected by the spring plank 174 preferably flanged as at 176. The bolster 178 extends within the side frame, being provided with guides 180 cooperating with the column guides 168, the bolster being provided with the center bearing 181 and side bearings 183.

Within the opening formed in the side frame there is provided an anti-friction bearing seat 182 fixed with respect to the side frame. A movable seat 184 is provided, spaced by means of 50 the anti-friction rollers 186. The member 184 provides spaced coil spring seats 188 adjacent the column guides adapted to accommodate the coil springs 190, the other end of the coil springs seating in coil spring seats 192 provided in the end 55

of the bolster. The bolster is provided with spaced leaf spring seats 194 provided therein and spaced between the side frames for accommodating the leaf or semi-elliptic springs 196, said leaf 5 spring seats 194 being substantially in vertical alignment with the side bearings 183. The outer ends of the springs are provided with a shoe 198 disposed in seat 200 provided in the member 184, the opposite ends of the leaf springs being provided with a suitable shoe 202 disposed in a seat 204 provided in the bolster.

In the construction illustrated in Figure 4 the end of the bolster outwardly of the seat 204 is substantially inverted U-shaped, being provided with 15 the depending coil spring seats 192 provided on the bolster. In the construction illustrated in Figure 5, however, the bolster is substantially box-shaped throughout its entire length, being apertured as at 206 to permit passage of the semi- 20 elliptic leaf spring 210 therethrough, coil spring seats 208 being provided adjacent the ends in a similar position to the coil spring seat 192. The leaf spring seats adjacent the outer end as at 212 on the seat 200 of the rollers 186, and the spring 25 band 214 of the leaf spring supportingly engages the seat 216 provided in the bolster. The inner end of the leaf spring engages the inner bolster seat 218, the end of the bolster being substantially uninterrupted as at 220.

30 With construction such as shown herein, an economical truck is provided, and one making for ease in riding qualities. The elliptic springs, working together with the coil springs, prevent oscillation or bouncing of the truck and car by 35 virtue of the friction between the leaves of the elliptic springs. Thus increased spring capacity is obtained without requiring additional sets of springs, as would be the case if elliptic springs and coil springs supported the loads independently. The elliptic springs produce a dampening effect by rebuking the harmonic action of the coil springs. The movable bolster, in the combination set forth, permits the car to roll or oscillate transversely without a great tendency 40 to force the wheel over the rail, as would be the case were the bolster rigidly fixed to the truck.

It is to be understood that I do not wish to 50 be limited by the exact embodiments of the device shown, which are merely by way of illustration and not limitation, as various and other forms of the device will of course be apparent to those skilled in the art without departing from the spirit of the invention or the scope of the claims.

55 I claim:

1. In a truck, the combination of a side frame having tension and compression members and column guides therebetween forming an opening therein, a bolster extending into said opening 60 and cooperating with said column guides, coil springs disposed between said bolster and said tension member, and a leaf spring disposed between said coil springs, said leaf spring being seated at two points on said bolster and supported at one point on said side frame, said points being spaced apart longitudinally of said spring.

2. In a truck, the combination of a side frame having tension and compression members and 70 column guides therebetween forming an opening therein, a bolster extending into said opening and cooperating with said column guides, coil springs disposed between said bolster and said tension member, a leaf spring disposed between 75 said coil springs, said leaf spring being seated at

two points on said bolster and supported at one point on said side frame, said points being spaced apart longitudinally of said spring and anti-friction members between said springs and side frame.

3. In a truck, the combination of a side frame having tension and compression members and column guides therebetween forming an opening therein, a bolster extending into said opening and cooperating with said column guides, coil 10 springs disposed between said bolster and said tension member, and leaf springs disposed between said coil springs, said leaf springs being seated intermediate their length on said bolster, one end of said leaf springs seating on said side 15 frame, the other end of said leaf springs being linked to said bolster.

4. In a truck, the combination of a side frame having tension and compression members and column guides therebetween forming an opening 20 therein, a bolster extending into said opening and cooperating with said column guides, coil springs disposed between said bolster and said tension member, and leaf springs disposed between said coil springs, said leaf springs being 25 seated intermediate their length on said bolster, one end of said leaf springs seating on said side frame, the other end of said leaf springs being seated on said bolster.

5. In a truck, the combination of a side frame 30 having tension and compression members and column guides therebetween forming an opening therein, anti-friction means seated on said truck member, a bolster extending into said opening and cooperating with said column guides, coil 35 springs disposed between said bolster and said anti-friction means and seated on said means, and leaf springs disposed between said coil springs, said leaf springs being seated intermediate their length on said bolster, one end 40 of said leaf springs being seated on said bolster, the other end of said leaf springs being seated on said anti-friction means.

6. In a truck, the combination of a side frame, a load carrying member, resilient means of different character mounted on said side frame and each engaging said load carrying member, one of said resilient means seating on seats on 45 said load carrying member at a plurality of points, said points being spaced longitudinally 50 of said load carrying member, and lateral motion means interposed between said side frame and said resilient means.

7. In a truck, the combination of spaced side frames, a load carrying member, and an independent spring assembly at each side of said truck arranged to directly support said load carrying member on each of said side frames, said spring assemblies each including a semi-elliptic spring, a coil spring and lateral motion 60 means, said semi-elliptic spring being disposed transversely of said truck and seated on seats carried by said load carrying member and spaced longitudinally of said load carrying member.

8. In a truck, the combination of a side frame, 65 a load carrying member, and resilient means of different character arranged in parallel to support said load carrying member on said side frame, said resilient means including a semi-elliptic spring disposed transversely of the truck 70 and directly engaging seats carried by said load carrying member at a plurality of points and spaced longitudinally of said load carrying member.

9. In a truck, the combination of a side frame, 75

a load carrying member, and resilient means of different character arranged in parallel to support said load carrying member on said side frame, said resilient means including a semi-elliptic spring disposed transversely of the truck and supported on said side frame at a single point and directly engaging seats carried by said load carrying member at a plurality of points and spaced longitudinally of said load carrying member.

10. In a railway car truck, opposite side frames, springs carried in said side frames, a bolster extending between said side frames with its ends supported on said springs, and additional bolster supporting means comprising a cantilever spring having its inner end engaging a formation on said bolster and its outer end supported on a side frame.

11. In a railway car truck, opposite side frames, helical springs carried in said side frames, a bolster extending between said side frames with its ends supported on said helical springs, and additional bolster supporting means comprising a leaf spring having its inner end engaging a formation on said bolster and its outer end supported on a side frame.

12. In a railway car truck, opposite side frames having windows therein, a spring plank joining said side frames at said windows, coil springs carried in the windows of said side frames, a bolster supported at all times on said springs, and additional bolster supporting springs disposed outside said windows between said bolster and spring plank, said latter springs engaging the bolster on seats spaced longitudinally of said latter springs, said latter springs acting in parallel with the first mentioned springs.

13. In a railway car truck, opposite side frames having windows therein, springs seated within said windows, a bolster extending between said side frames with its ends supported on said springs, and additional bolster supporting means comprising cantilever springs having their inner ends engaging formations on said bolster and their outer ends supported on said side frames at the seats for said first mentioned springs.

14. In a railway car truck, opposite side frames having windows therein, a spring plank joining said side frames at said windows, seat members superposed upon the ends of said spring plank at said windows, springs mounted on said seat members, a bolster extending between said side frames with its ends supported on said springs, and additional bolster supporting means comprising springs of a different kind positioned between said spring plank and bolster and disposed transversely with respect to said side frames and with certain of their ends engaging the seat members aforesaid, the opposite ends of said last-named springs engaging said bolster.

15. A bolster having a center bearing and spaced side bearings, said bolster having a substantial box section between said side bearings and being of substantially inverted U-section outwardly thereof, leaf spring seats, certain of said seats being formed in said bolster substantially in the plane of said side bearings and other of said seats being formed substantially inwardly thereof, and spring seats formed on the ends of said bolster.

16. A bolster having a center bearing and spaced side bearings, said bolster having a substantial box section between said side bearings and being of substantially inverted U-section out-

wardly therof, leaf spring seats, certain of said seats being formed in said bolster substantially in the plane of said side bearings and other of said seats being formed substantially inwardly thereof, and coil spring seats formed on the ends of said bolster.

17. A bolster having center and side bearings, said bolster being a substantial box section between its ends, said box section being formed by an upper compression member and a lower tension member and spaced side members integrally connecting said tension and compression members, leaf spring seats provided on said tension member and side members, and coil spring seats formed adjacent the ends of said bolster and on said tension member.

18. A bolster having a center bearing and spaced side bearings, said bolster being a substantial box section between the ends thereof, said bolster being provided with an aperture substantially in vertical alignment with said side bearings, spring seats formed in said box section adjacent said aperture and substantially in vertical alignment with said side bearings, and coil spring seats formed on the ends of said bolster.

19. In a truck, the combination of side frames having spaced journal boxes, a load carrying member, and resilient means of different character arranged on each side of said truck for supporting said load carrying member on said side frames, said resilient means each including a semi-elliptic spring disposed longitudinally of said load carrying member and only supported by said side frame at a single point and other means of different character than said spring disposed in parallel therewith, said means being supported on spaced seats on said side frame, said seats being spaced from said journal boxes.

20. A bolster having a center bearing and spaced side bearings, said bolster having a substantial box section between said side bearings, and being of substantially inverted U-section outwardly thereof, spring seats formed in said box section substantially in vertical alignment with said side bearings, and spring seats formed on the ends of said bolster outside said U-section and spaced from said side bearings.

21. A bolster having a center bearing and spaced side bearings, said bolster having a substantial box section between said side bearings and being of substantially inverted U-section outwardly thereof, spring seats formed in said box section substantially in vertical alignment with said side bearings, and coil spring seats formed on the ends of said bolster outside said U-section.

22. A bolster having a center bearing and spaced side bearings, said bolster having a substantial box section between said side bearings and being of substantially inverted U-section outwardly thereof, leaf spring seats formed in said box section substantially in vertical alignment with said side bearings, and spring seats formed on the ends of said bolster and spaced from said side bearings and outside said U-section.

23. A bolster having a center bearing and spaced side bearings, said bolster having a substantial box section between said side bearings and being of substantially inverted U-section outwardly thereof, leaf spring seats formed in said box section substantially in vertical alignment with said side bearings, and coil spring seats formed on the ends of said bolster outside said U-section.

24. A bolster having a center bearing, spaced side bearings and column cooperating portions,

said bolster having a substantial box section between ~~said~~ side bearings and being of substantially inverted U-section outwardly thereof, spring seats formed in said box section substantially in vertical alignment with said side bearings, and spring seats formed on the ends of said bolster outside said U-section.

25. A bolster having a center bearing, spaced side bearings and column cooperating portions, leaf spring seats formed within said bolster substantially in vertical alignment with said side bearings, and non-resilient spring seats formed

on the outside of said bolster and adjacent the ends thereof.

26. A bolster having a center bearing, spaced side bearings and column cooperating portions, said column cooperating portions having spring seats, said bolster having a plurality of longitudinally spaced seats between the center bearing and each of the ends of the bolster for accommodating a leaf spring on each side of said center bearing. 10

FRED E. BACHMAN.
